UNITED STATES PATENT OFFICE.

SIDNEY A. KELLER, OF NEW YORK, N. Y., ASSIGNOR TO JACOB BERNHEIM, OF NEW YORK, N. Y., TRADING AS WOODSIDE STERLING COMPANY, A FIRM.

DESIGN FOR A BACK OF HAND-MIRRORS OR SIMILAR ARTICLES.

No. 87,778.

Specification for Design.

Patented Jan. 9, 1906.

Application filed December 2, 1905. Serial No. 290,454. Term of patent 7 years.

To all whom it may concern:

Be it known that I, SIDNEY A. KELLER, a citizen of the United States, and a resident of New York, borough of Manhattan, in the county of New York and State of New York, have invented a certain new, original, and ornamental Design for the Back of a Hand-Mirror or Similar Article, of which the following is a specification.

The accompanying drawing is a view in elevation of the back of a hand-mirror having my design applied thereto.

What I claim is—

The ornamental design for the back of a hand-mirror or similar article, as shown.

SIDNEY A. KELLER.
